UNITED STATES PATENT OFFICE.

HARRY GREENER, OF BIRMINGHAM, ENGLAND.

SHOT CARTRIDGE.

Application filed April 11, 1927, Serial No. 182,848, and in Great Britain April 1, 1926.

According to the present invention, which relates to shot cartridges for use with sporting guns, the portion of the case that contains the shot-charge is, for the whole or 5 the greater part of its length, reduced in diameter compared to the part that contains the powder-charge. In other words, the case is formed with a bottle neck or is made smaller in diameter for a distance from its 10 shot-wad end, and this bottle-neck portion contains the whole or the greater part of the charge of shot and the shot-wads whilst the powder or propellant charge and powder wads contained in the larger or body part of 15 the case; the shoulder formed by such necking where the bottle-neck joins or merges into the main body being utilized to retain the powder wads in place in front of the propellant charge and to impose resistance 20 on the displacement of such wads. With such a cartridge, when loaded into the chamber of a gun, the neck or reduced portion is surrounded by an annular space.

The accompanying drawing shows a shot 25 cartridge in accordance with an application of my invention, Figure 1 being an elevation of the same, Figure 2 a cross-section through the neck (the shot being omitted) and Figure 3 a complete longitudinal section of the cartridge on the dotted line 3—3, Figure 2.

Preferably necking or reduction of the shot-containing part a^1 of the case a is performed after the loading of the propellant 35 charge b and the seating of the powder wads c on the latter, and to facilitate this necking by a spinning-down operation (particularly in a paper case) the part that is to be spun down or necked and shouldered over the 40 powder-wads may first be formed with a series of longitudinal grooves or inward indentations along the lines d , and these grooved portions are, in the course of the necking or spinning down operation, closed 45 up or crimped, or transformed into closed gussets (see Figure 2), which gives the bottle-neck the capacity of readily expanding to its original diameter when the cartridge is fired. e is the shot charge and f the shot 50 wads, which are held in place by the turnover g of the neck. Such bottle-necked shot cartridges are intended to be used in shot guns whose barrels have the ordinary parallel-bored or cylindrical chambers so 55 that the chamber does not resist expansion of the neck on discharge, and a suitable re-

duction would be one in which the neck is approximately two bore sizes smaller than the body of the case. Thus a cartridge for a 12-bore gun may be reduced over the shot-containing neck to 14-bore; or the reductions may be to 16-bore or even smaller in cartridges for loading with large charges; it being understood that the greater the reduction over the shot, the wider or more 60 pronounced is the annular shoulder or stepping over the powder wads, and the greater the resistance imposed on the said wads by the necking.

The principal advantage realized by the 70 said invention is reduction of the pressure on the starting of the shot charge; the resistance set up by the shouldering of the case over the powder wads being such as to control the combustion of the powder in a manner which permits the column of shot to leave the necking of the case and become shortened in length on filling up the full diameter of the barrel-bore before the powder gases can develop higher or increasing 80 pressures.

Thus the improved shot cartridge realizes better ballistics than the usual type of cylindrical cartridge, and incidentally, by reason of the necking, it is easier to load into 85 a gun and easier to eject. The forward end is also easily distinguished by touch or feeling owing to the said necking.

The better ballistics may be utilized to improve patterns, or to obtain higher velocities with improved patterns, or to permit of highly increased velocities being realized by the use of large charges of powder or propellant. These improvements in shooting qualities are attributable to the fact 90 that the formation and the manner of loading the powder and shot charges and wads permits, on ignition of the powder charge, of the shot making a true rolling movement under an initial or starting pressure which 100 is or may be less than the maximum pressure developed by the same powder charge in an ordinary case; this rolling of the shot being maintained during the passage 105 of the shot from the cartridge into the barrel, which prevents the charge of shot being compacted or jammed together and avoids the distortion (such as occurs with ordinarily loaded cases) of the individual pellets from their true spherical form. 110 Thus, given a suitable proportioning of the bottle-necking and the body of the case, it

- is possible to realize low initial resistance (which results in lower initial pressures and lower initial velocity) during the passing of the rolling shot from the cartridge case 5 into the barrel and to provide for a gradual rise of pressure to the maximum as the shot column fills up and shortens in the said barrel. Consequently, although the shot acquires a high velocity, the development of 10 the powder gas pressure is gradual or increases progressively as the shot passes along the barrel without at any time rising unduly in proportion to the velocity attained.
- 15 The shot wads may be retained in the bottle-neck by a light turn-over so that in effect there is practically no resistance over the shot-charge; the effective resistance in the cartridge being imposed directly on the 20 powder-wads by the shouldering of the case over the latter during the reduction of the neck.

Having described my invention, what I claim and desire to secure by Letters Patent is: —

25 A shot gun cartridge comprising a shell having a cylindrical body portion of a diameter corresponding to that of a gun chamber, said shell also having a diametrically reduced neck provided with longitudinal crimpings and a shoulder connecting said neck and said body, a powder charge in said body, a shot charge in said neck and wads between said charges, the foremost 30 of which bears against said shoulder, the 35 said cartridge when loaded in a gun chamber by reason of said reduced neck providing an annular space surrounding said neck and between the neck and the said chamber, the said longitudinally extending crimps 40 enabling the said neck to diametrically expand when the cartridge is fired.

In witness whereof I affix my signature.

HARRY GREENER.
